UNITED STATES PATENT OFFICE

154,683

DESIGN FOR A MEAT MOLD COVER OR
SIMILAR ARTICLE

Frank H. Hoy, Milwaukee, Wis., assignor to Hoy
Equipment Co., Milwaukee, Wis., a corporation
of Wisconsin

Application October 31, 1946, Serial No. 134,407

Term of patent 14 years

(Cl. D11—1)

To all whom it may concern:

Be it known that I, Frank H. Hoy, a citizen of the United States and a resident of the city of Milwaukee, in the county of Milwaukee and State of Wisconsin, have invented a new, original, and ornamental Design for a Meat Mold Cover or Similar Article, of which the following is a specification, reference being had to the accompanying drawing, forming a part thereof.

On the drawing:

Figure 1 is a top plan view of a meat mold cover or similar article, showing my new design.

Figure 2 is a side elevational view, and

Figure 3 is an end view thereof.

I claim:

The ornamental design for a meat mold cover or similar article, as shown.

FRANK H. HOY.
